UNITED STATES PATENT OFFICE

172,589

GARMENT HANGER

Richard B. Friedman, Cleveland, and Joseph T. Lee, Cleveland Heights, Ohio, assignors to Freely, Inc., Cleveland, Ohio, a corporation of Ohio

Application August 26, 1953, Serial No. 26,588

Term of patent 14 years

(CL. D80—8)

To all whom it may concern:

Be it known that we, Richard B. Friedman and Joseph T. Lee, citizens of the United States, have invented a new, original, and ornamental Design for a Garment Hanger, of which the following is a specification, reference being had to the accompanying drawing, forming a part thereof.

Fig. 1 is a top plan view of a garment hanger showing our new design,

Fig. 2 is a rear elevation thereof, and

Fig. 3 is a side elevation showing our new design from the outside.

We claim:

The ornamental design for a garment hanger, substantially as shown.
